UNITED STATES PATENT OFFICE.

FRANK A. AUSTIN AND ALLEN CLYMER AUSTIN, OF SYRACUSE, NEW YORK.

PRESSING-MACHINE.

1,233,293.

Specification of Letters Patent.

Patented July 10, 1917.

Application filed August 7, 1914. Serial No. 855,549.

To all whom it may concern:

Be it known that we, FRANK A. AUSTIN and ALLEN CLYMER AUSTIN, citizens of the United States, and residents of Syracuse, in the county of Onondaga and State of New York, have invented a certain new and useful Pressing-Machine, of which the following is a specification.

This invention relates to garment pressing machines having upper and lower steam heated bucks or pressing members, and it has for its object a particularly simple and efficient arrangement of steam chambers on one of the bucks by which the buck is kept hot and the steam passed through the perforations therein and through the garment. Another object is the simplifying of the construction and operation of garment pressing machines. Other objects will appear throughout the specification. The invention consists in the combination and constructions hereinafter set forth and claimed.

In describing this invention, reference is had to the accompanying drawings, in which like characters designate corresponding parts in all the views.

Figure 1 is a sectional view through the bucks and contiguous parts.

Fig. 2 is a plan of the machine, partly broken away.

Fig. 3 is a side elevation thereof.

Fig. 4 is a section on line 4—4, Fig. 3.

Fig. 5 is a detail view in plan of the lower section of the lower buck, a fragmentary portion of the upper section being shown.

Fig. 6 is a central longitudinal sectional view taken through the lower section of the lower buck. Fig. 7 is a plan partly in section of the standard illustrating the relative positions of the treadles.

Figs. 8 and 9 are opposite views of the baffle plate.

Fig. 10 is a detail fragmentary view illustrating the steam connection at the pivot of the upper buck.

This machine comprises, generally, a frame, upper and lower bucks supported by the frame, the upper buck being movable toward and from the lower buck, means for operating the upper buck and means for controlling the flow of steam to one of the bucks for the purpose of steaming the garments.

1 is the frame consisting of three legs 2 and a table 3 mounted on the legs, and bearing thereon at three points 4, 5 and 6; Fig. 2.

7 is a bracket rising from the table 3, and 8 is the lower buck or pressing bed mounted on the bracket, the bracket having three points 9 on which the buck 8 rests, and also having three bearing points 10 on the table. 60

12 is the upper buck or pressing head which is movable toward and from the lower buck and is supported by a lever frame 13 pivoted at 14 to standards 15 rising from the rear side of the table 3. The lever is actuated as will be hereinafter described and has three bearing points 13^a on the buck 12. Either or both bucks may be constructed to emit steam through the garments, but preferably the lower buck is so constructed, and as seen in Fig. 1, the lower buck 8 is formed with a heating chamber 16, a second chamber 17 located above the heating chamber and having perforations in its top wall extending through the face of the buck for the outlet of steam, a main inlet pipe 18 leading into the chamber 16 and a conduit 19 opening into the chamber 17 and connected to the chamber 16 to receive steam therefrom. 70

As here shown, the chamber 17 includes a depressed portion 20 extending lengthwise of the chamber 16 centrally thereof, and in which lies the intake pipe 19; and a baffle plate 21 is inserted between the depressed portion 20 and the perforations 22 in the top of the chamber 17, the baffle plate being held as hereinafter described, off the bottom of the chamber 17 and away from the top thereof so that the steam can pass from the depression 20 of the chamber 17 around the edges of the baffle plate and through the perforations 22, the edges of said plate 21 being spaced apart from the edges of the chamber 17. The perforations 22 are preferably of the form shown in order that any water of condensation will not pass through the same. The plate 21 serves to separate any water of condensation from the steam before the steam passes through the perforations, and the chamber 16 acts as a steam dome, and also as a superheater for the steam in the chamber 17. 90

As here shown, the buck 8 consists of lower and upper sections 23, 24, the lower section 23 being formed with the internal chamber 16 and with the lengthwise depression 20 opening through its upper face; and the upper section 24 is a perforated plate arranged so that its intermediate portion, which is perforated, is spaced apart from the 100

110

upper face of the section 23; the sections being held together at their margins by screws 25, Fig. 4. A suitable gasket 25^a is inserted between said margins to prevent the leakage 5 of steam. The plate 21 is arranged between the sections.

As here shown, opposing faces of the sections 23, 24 are recessed slightly in order to form the chamber 17 which is very low or 10 flat, and the upper face of the section 23 is formed with beads or ridges 26, Figs. 1 and 5, around the central depression 20 and on which the plate 21 rests, the plate being formed with lugs 27 which fit one of the ribs 15 26. The plate is held from being raised too far by the steam and from closing some of the perforations, by means of springs 28 inserted between said baffle plate 21 and the upper section 24. The springs permit the 20 plate to be raised off the beads sufficiently to let the steam pass from the depression 20 over the beads or ridges. The intake pipe 18 is connected to a suitable boiler and the steam is led to the chamber 16 through 25 passage 29 and thence into the chamber 17 through passages 30, 31, Fig. 4, the pipe 18 being connected to the lower end of the passage 29, and the lower end of the passage 30 being connected to the pipe or yoke 32 which 30 also communicates with the lower end of the passage 31 and which is provided with a suitable control valve 33.

34, 35 are drain passages leading from the chamber 16 and yoked together at 36 and 35 connected to a pipe 37 leading back to the boiler. The passages 29, 30, 31, 34 and 35 have continuations 29^a, 30^a, 31^a, 34^a, 35^a through the lower buck 8. The passages 29^a and 30^a extend through projections in the 40 chamber 16 on the bottom thereof, said projections having lateral outlet and inlet passages 38, 39. By reason of the passages 38, 39 which are located above the bottom of the steam chamber 16, the water of condensation will not flow back through the 45 passages 29, 30, but will flow through the passages 34, 35. The inlet pipe 19 is coupled to the upper end of the passage 31, that is, the extension 31^a and extends lengthwise of the 50 depressed portion 20 of the chamber 17 and is formed with jet openings 40 through which the steam is discharged and also with an opening 40^a at its extreme end through which any water is expelled, there naturally 55 being more water at the end of the pipe than at the intermediate part so that any water at the end of the pipe will be forced out and converted into steam when it strikes the hot walls of the depression 20 which are being 60 heated by the live steam in the chamber or dome 16. The portion of the depression beyond the inner end of the pipe 19 is formed with a top wall 20^a integral with the lower section 23, and forming a superheating 65 chamber pocket, or dome in which the water

of condensation is converted into steam. The passages 29, 30, 31, 34 and 35 are formed in a metal block 9^a depending from the underside of the lower buck 8 and bolted thereto. 70

The upper buck 12 is formed hollow with bracing blocks or pillars 12^a between its upper and lower walls and has connected thereto a single inlet pipe 41 which is connected to the pipe 42 arranged coaxially with the 75 axis of the lever 13 supporting said buck 12 in order to provide a swivel joint for the pipe 41, the pipe 41 being connected to the intake 43 leading back to the boiler or other source of steam supply. The pipe 41 serves 80 both as an inlet and a drain for the water of condensation as the pressure is neutral therein and when the buck is in its upper position shown in Fig. 3 the water will flow out of the same. Both bucks are covered with 85 suitable cloths and strips of felt. The bucks also have suitable heat retaining covers of asbestos compound.

The means for actuating the buck 12 consists of a treadle in the form of a lever 45 pivoted between its ends, one arm 46 extending forwardly and the other being inclined upwardly and forming one link of a toggle, the other link 47 of which is pivoted at 48 to the rear arm of the frame 13, the links 46, 47 95 being pivoted together at 49, and said rear arm of the frame and the toggle link 47 being normally arranged in a straight line, when the upper buck is in its elevated or starting position. The lever frame 13 has a 100 weight 50 in the rear of its axis for returning the buck 12 to its open position. Said link 47 also includes a right and left hand screw thread connection 51 as a rod threaded at both ends and by which the link can be 105 adjusted lengthwise in order to adjust the joint of the toggle toward and from the dead center line of the toggle and hence regulate the leverage to the man operating the machine. The lever 13 and the link 47 are 110 normally held in a straight line and from relative movement in a retrograde direction by means of a stop shoulder or latch 52 pivoted at 53 to the lever 13 and coacting with a shoulder 54 on the link 47, the shoulders 115 52, 54 being located on opposite sides of the joint 48 between the rear arm of the buck frame lever and the link 47 of the toggle. When this stop shoulder is in its position shown in Fig. 3 the upper buck 12 cannot be 120 swung farther upwardly, but upon the removal of the stop by operating the link 55, the buck 12 can be swung backwardly so that the lever 13 is in a vertical line, and the buck 12 is out of the way when the operator 125 desires to steam cloth or garments on the lower buck without pressing the same.

The valve 33 is operated by means of a pedal 56 pivoted at 57 to the frame and connected by means of a cord 58 and a lever 130

59, to the valve 33. This pedal 56 is arranged to be operated to open the valve 33 upon the depression of the pedal 45, but at times it is desired not to pass steam 60 through the garments and hence it is desirable that the pedal 56 be not actuated upon each depression of the pedal 45. In order that this pedal 56 may be depressed at will by the same foot operating the pedal 45, the 65 pedal 45 is provided at its front end with a pivoted foot piece 60 pivoted at 61 and movable on its pivot 61 so that the toe of the shoe of the operator will depress the pedal 56 when the pedal 45 is in lowermost position, as shown in dotted lines in Fig. 3. The pedal 56 is also formed with a lateral extension 62 by means of which it can be operated conveniently when the treadle 45 is not operated as when it is desired to 70 steam garments without pressing them and the buck 12 is swung upwardly so that its supporting frame 13 is in vertical position. The movement of the pedal 56 and hence the extent to which the valve 33 is opened 75 is regulated by an adjustable stop 56^a carried by the pedal 56 and coacting with a fixed part of the frame.

When the machine is not in use and it is 80 desirable to keep the bucks hot, the treadle 45 is depressed to move the upper buck onto the lower, and a latch 45^a, Fig. 7, pivoted to the frame or a crossbar thereof, is swung over the lever 45 to hold the same depressed. The latch is arranged so that it hangs normally out of operative position.

In use, the operator places the garment upon the buck 8 and depresses the treadle 45 by placing his foot upon the foot piece 60, this movement moving the joint of the 40 toggle forwardly toward the dead center line of the toggle and moving the link 47 out of a straight line with the rear arm of the lever 13 so that said lever is tilted on its pivot 14 and the upper buck 12 is brought down upon the garment on the lower buck 8. For an operator of light weight, the link 47 is shortened so that the joint of the toggle will move easier into the straight line than when the link is longer. To eject 50 steam into the clothes held between the bucks, the operator moves his foot to shift the foot piece 60 on its pivot 61 so that the toe of his shoe will operate the pedal 56 which is connected to the valve 33 to open the same.

When the operator removes his foot from the treadle 45, the parts are returned to their normal position by the weight 50 and spring 50^a which is connected to the treadle 60 45 and to the frame. When it is desired to steam cloth or garments without pressing them, the upper buck may be swung out of the way by moving the stop shoulder 52 on its pivot 53 out of engagement with the shoulder 54 so that the lever frame 13 will

be carried by its weight 50 into vertical position without materially changing the position of the treadle 45 and arm 46 thereof.

The shoulder 52 is operated on its pivot 53 by means of the link 55 which extends 70 forwardly to the front side of the upper buck where it can be conveniently taken hold of by the operator. The upper buck is also provided with a suitable handle by means of which it can be started toward its 75 closed position.

Owing to the arrangement of the chambers and steam connections in the lower buck, the bucks are heated and the water of condensation eliminated therefrom in a 80 particularly simple and economical manner. Owing to the arrangement of the pedal for controlling the steam valve with respect to the treadle for operating the upper buck, a much simpler machine is provided, which 85 is readily operated without unnecessary movements on the part of the operator, and owing to the arrangement of the toggle and its adjustable link with respect to the frame of the upper buck, the leverage of the upper buck can be adjusted to the operator; and further, owing to the relative arrangement 90 of the frame for the upper buck and the toggle links and to the locking part 52, the upper buck can be swung into vertical position without disarranging other parts of the machine.

This machine is particularly advantageous in that it consists of a few parts, is 95 readily operated without unnecessary movements on the part of the operator, and further in that it is economical in fuel and steam owing to the arrangements of its steam chamber and connections.

What we claim is:—

1. A garment pressing machine comprising a buck having a heating chamber, a second chamber having perforations opening through the face of the buck, the second chamber having a portion located in the heating chamber, an inlet connected to the heating chamber, and an outlet leading from the heating chamber, and connected to the interior of the second chamber, substantially as and for the purpose set forth.

2. A garment pressing machine comprising a buck having a heating chamber therein, a second chamber overlying the heating chamber and having perforations opening through the face of the buck and also having a portion extending lengthwise of the buck centrally thereof and located in the horizontal plane of the heating chamber and being embedded in the heating chamber and having walls exposed in said heating chamber, and feed pipes connected to the heating chamber and to the depressed portion of the second chamber, substantially as and for the purpose set forth.

3. A garment pressing machine comprising

105

100

105

110

115

120

125

130

- ing a buck having a heating chamber therein, a second chamber overlying the heating chamber and having perforations opening through the face of the buck and also having a portion extending lengthwise of the buck centrally thereof and located in the horizontal plane of the heating chamber and embedded in the heating chamber so that the walls thereof are exposed to the steam in the heating chamber, a feed pipe connected to the heating chamber, and a conduit connecting the first chamber and the depressed portion of the second chamber, substantially as and for the purpose described. 5 70
15. A garment pressing machine comprising a buck having a heating chamber, a second chamber overlying the heating chamber and having a perforated top, the second chamber having a depressed portion extending lengthwise of the buck and being located in the heating chamber so that the walls of the depressed portion are exposed in the heating chamber, an intake pipe connected to the heating chamber, a conduit leading 10 75
- 20 from the heating chamber and opening into the depressed portion of the second chamber, and a plate located in the second chamber between the bottom and top thereof, substantially as and for the purpose described. 80
- 25 15. A garment pressing machine comprising a buck having a heating chamber, an intake conduit leading to the heating chamber, an outlet leading therefrom, the inlet and outlet communicating with the heating chamber above the bottom thereof, and a drain pipe leading from the bottom of the heating chamber, substantially as and for the purpose specified. 85
- 30 16. A garment pressing machine comprising a buck having a heating chamber, a second chamber having a wall formed with perforations which open through the face of the buck, inlet and outlet conduits communicating with the heating chamber above the bottom thereof, the outlet of the heating chamber being connected to the second chamber to supply steam thereto, and a drain leading from the bottom of the heating chamber, substantially as and for the purpose described. 90
- 35 17. A garment pressing machine comprising a buck having a heating chamber, a second chamber overlying the heating chamber and having a depressed central portion extending lengthwise of the buck centrally thereof and located in the horizontal plane of the first chamber, a feed pipe connected to the first chamber and a conduit connecting the first chamber and the second chamber 95
- 40 and extending lengthwise of the depressed portion thereof and opening into the same, substantially as and for the purpose specified. 100
- 45 18. A garment pressing machine comprising a lower buck having a steam chamber, a 105
- 50 detachable block depending from the buck and formed with passages communicating with the steam chamber, and pipes connected to the passages, substantially as and for the purpose set forth. 110
- 55 19. A garment pressing machine including a buck having a heating chamber, a second chamber overlying the heating chamber and having a perforated top, an inlet pipe connected to the heating chamber, a conduit connecting the heating chamber and the second chamber, and a plate in the second chamber between the inlet for the steam therein and the perforated wall thereof, the plate being of slightly less dimensions than the portion of the chamber in which it is arranged and terminating near the ends and the sides of said second chamber with its marginal edges spaced apart from the edge walls of the chamber whereby the steam passes around the edges of the plate and out through the perforations, substantially as and for the purpose set forth. 115
- 60 20. A garment pressing machine comprising a buck including two sections, one being formed with an internal chamber and the other comprising a plate mounted on the first section and together therewith forming a chamber between the sections, means for supplying the steam to the internal chamber and to the space between the sections, and a floating baffle plate located between the sections and being slightly less in dimensions than the dimensions of the chamber formed between said sections and arranged with its margins spaced apart from the end walls of the chamber formed between the sections, substantially as and for the purpose described. 120
- 65 21. A pressing machine comprising a frame having three bearing points, a table mounted on said three bearing points, a buck, a bracket supporting the buck and having three bearing points on the table, substantially as and for the purpose specified. 125
- 70 22. A pressing machine comprising a frame having three bearing points, a table mounted on said three bearing points, a bracket mounted on the table and having three bearing points on the table, and a buck mounted on the bracket and having three bearing points thereon, substantially as and for the purpose set forth. 130
- 75 23. A garment pressing machine comprising a buck having a heating chamber, a second chamber overlying the heating chamber and having a perforated top, an intake conduit opening into the second chamber, and the second chamber being formed with a pocket the walls of which are surrounded by the heating chamber, the intake conduit having a water outlet in the pocket, substantially as and for the purpose described. 135

14. A garment pressing machine comprising a buck having a heating chamber, a second chamber overlying the heating chamber and having a perforated top, an intake pipe connected to the heating chamber, and a conduit leading from the heating chamber and opening into the second chamber, and the second chamber being formed with a pocket the walls of which are surrounded by the heating chamber, the conduit having a water outlet in the pocket, substantially as and for the purpose specified.

15. A garment pressing machine comprising a buck having a heating chamber, a second chamber overlying the heating chamber and having a perforated top, the second chamber having a depressed portion extending lengthwise of the buck and surrounded by the heating chamber, one end of the depressed portion having a top wall forming a pocket, and an intake pipe for the chambers including a conduit leading into the depressed portion of the second chamber and having a water outlet arranged to discharge into the pocket, substantially as and for the purpose set forth.

16. A garment pressing machine comprising a buck having a heating chamber, a second chamber overlying the heating chamber and having a depressed portion 30 extending lengthwise of the buck, and surrounded by the heating chamber, one end of the depressed portion having a top forming a pocket, a feed pipe connected to the first chamber, and a conduit connecting the first chamber and the second chamber and extending lengthwise of the depressed portion thereof and opening into the same and having outlets thereinto, the pipe also having a jet discharging into the pocket, substantially as and for the purpose described.

In testimony whereof, we have hereunto signed our names in the presence of two attesting witnesses, at Syracuse, in the county of Onondaga, in the State of New York, 45 this 30th day of July, 1914.
